(57) **CLAIM**

The ornamental design of a vaginal shield, as shown and described.

DESCRIPTION

FIG. 1 is a perspective view of a vaginal shield, showing the novel vaginal shield design.

FIG. 2 is a top view of the vaginal shield design.

FIG. 3 is a bottom view of the vaginal shield design.

FIG. 4 is a side view, taken looking at the right side of the vaginal shield design

FIG. 5 is a side view, taken looking at the left side of the vaginal shield design.

FIG. 6 is a top plan view of the vaginal shield design; and,

FIG. 7 is a bottom plan view of the vaginal shield design.

In each of the drawing figures, the portions of the vaginal shield that are shown in broken lines are for illustrative purposes only and form no part of the claimed design.

The characteristic feature of the design resides in the vaginal shield, namely a flexible disposal shield having sufficient volume and anatomically sized and shaped to receive and enclose adult female genitals.
